[57] CLAIM

The ornamental design for a shoe upper, as shown and described.

DESCRIPTION

FIG. 1 is a side elevational view of one side of a shoe upper according to my new design;

FIG. 2 is a side elevational view of the other side of a shoe upper as shown in FIG. 1;

FIG. 3 is a front elevational view of the shoe upper as shown in FIGS. 1 and 2;

FIG. 4 is a rear elevational view of the shoe upper as shown in FIGS. 1 and 2; and,

FIG. 5 is a top plan view of a shoe upper as shown in FIGS. 1 and 2.

The broken line showing of a shoe sole, including the cupped vertical sides of the sole, is for illustrative purposes only and forms no part of the claimed design.
